Frederick M. Breen, Westchester, N. Y., assignor to Coty,
Inc., New York, N. Y., a corporation of Delaware

Application September 27, 1954, Serial No. 32,453

Term of patent 14 years

(Cl. D58—6)

Fig. 1.

Fig. 2.

Fig. 3.

Fig. 4.

Figure 1 is a front view of a toilet water bottle or similar article showing my new design;

The design for the toilet water bottle disclosed is characterized by the curvatures of the sides as shown, in which the right side has a less pronounced curvature than the left side.

I claim:

The ornamental design for a toilet water bottle or similar article, substantially as shown and described.
